UNITED STATES PATENT OFFICE.

WILLIAM F. GREEN, OF HOUSTON, TEXAS.

COUPLING YOKE.

Application filed April 9, 1921. Serial No. 459,877.

To all whom it may concern:

Be it known that I, WILLIAM F. GREEN, a citizen of the United States, residing at Houston, in the county of Harris and State 5 of Texas, have invented certain new and useful Improvements in a Coupling Yoke, of which the following is a specification.

This invention relates to new and useful improvements in a coupler yoke.

10 One object of the invention is to provide a coupler yoke for railway cars through which the coupler stem may be attached to the car, said yoke being so constructed that it may be readily detached in case of break- 15 age so that the broken parts may be easily replaced.

Another object of the invention is to provide a coupler yoke of the character described which is readily demountable and 20 which is of simple construction so that it may be cheaply and easily manufactured and readily applied to or detached from the car.

With the above and other objects in view 25 the invention has particular relation to certain novel features of construction, operation and arrangement of parts, an example of which is given in this specification and illustrated in the accompanying drawings, wherein:—

30 Figure 1 is a plan view of the device.

Figure 2 is a perspective view.

Figure 3 is a perspective view of the filler block employed.

Figure 4 is a perspective view of one of 35 the yoke clamps employed, and

Figure 5 is a perspective view of one of the side members of the draft frame.

Referring now more particularly to the drawings, wherein like numerals of reference 40 designate similar parts in each of the figures, the numerals 1, 1 designate the side members of the draft frame which are spaced apart and are designed to be fastened to the sills of the car. The inner sides of 45 these members have the front and rear draft lugs 2 and 3, respectively, which form abutting shoulders against which the front and rear followers 4 and 5 normally rest. Interposed between these followers is the draft 50 spring 6. The yoke is formed of the upper and lower clamps 7 and 8. Between the rear ends of these clamps there is the filler

block 9 which is interlocked with the clamps, as shown in Figure 2, and a bolt 10 is passed upwardly through the clamps and the block to secure them together. The forward ends of the clamps are thickened inwardly forming the shoulders 11, 11, against which the front follower 4 normally rests. The coupler stem 12 is fitted between the forward ends of the yoke clamps and is secured therein by means of a bolt 13 which passes upwardly therethrough. The bolts 10 and 13 are secured against detachment by means of the keys 14, 14, which are held against accidental displacement by means of the set bolts 15, 15.

As the car is moving forwardly the follower 5 operates against the spring 6 which forms a yieldable cushion and when the car is being moved rearwardly the follower 4 operates against said spring, the spring acting as a yieldable cushion for absorbing the shock incidental to the operation of railway cars.

In case any part of the yoke should become broken the bolts 10 and 13 may be easily removed and the broken part replaced without dismembering the entire draft rigging. As at the present time constructed, 80 the draft yoke is formed of a single U-shaped member and in case of breakage the entire draft rigging must be dismembered and a new yoke substituted, thus requiring much time, labor and expense. By the use of the yoke hereinabove described this inconvenience and expense will be in a large measure avoided.

What I claim is:—

The combination with a draft frame 90 formed of side members spaced apart and whose inner sides have the front and rear draft lugs in transverse alignment, front and rear followers which rest against the front and rear lugs respectively, a draft spring between said followers, a yoke formed of upper and lower clamps, lugs carried by the facing sides of the rear ends of said clamps, a filler block between the rear ends of said clamps and formed with notches to receive said lugs, the forward ends of said clamps being thickened inwardly forming shoulders against which the front follower normally rests, a coupler stem fitted be- 95 100

tween the forward ends of the yoke clamps, bolts passing upwardly through the front and rear ends of said yoke, said bolts passing through said coupler stem and filler block respectively, keys fitted through the respective ends of said bolts and means for securing said keys against displacement.

In testimony whereof I have signed my name to this specification in the presence of two subscribing witnesses.

WILLIAM F. GREEN.
